COPYHOLDER

Edward L. Elliott, Arlington, Va., assignor to
 Federal Business Machines Corporation, Wash-
 ington, D. C., a corporation of Delaware

Application August 4, 1941, Serial No. 405,429

8 Claims. (Cl. 120—29)

This invention relates to improvements in copy holders.

Copy holders for use in conjunction with typewriters and other keyboard machines make use of a copy holding member of some sort, and a line indicating member, one of which is adapted to be moved, with respect to the other, by a suitable manual control, by successive increments equal to the line-spacing of the copy. On coming to the end of a page of copy, the movable member is returned to initial position, a suitable control being provided for this purpose.

One disadvantage of prior copy holders is that the controls are usually located rather far away from the keyboard, and moreover in some cases require complicated or unusual manipulation.

One object of the present invention is the provision of a copy holder of the class described, in which the operating controls are brought close to the keyboard in a convenient relation with respect thereto and in which the manual movement required for the controls is of the same general character as the movements involved in operating the typewriter, etc., no manipulation of a character different from that involved in typewriting being required. Another object is the provision of a copy holder of folding type in which the standard and copy holding member assembly is detachable from and attachable to the base assembly by a simple lifting movement, the controls on the base assembly, upon such attachment, automatically engaging the mechanism of said assembly without requiring any extra manipulation.

The apparatus of the invention includes a base plate, on which the typewriter or other machine rests, carrying at its rear edge a vertical standard (dismountable for folding) on which is guided telescopically a copy holding member, adapted to be raised, a line at a time. In the best embodiment of the invention, the raising means includes a lever, pivoted to the base plate for reciprocation in a horizontal plane, and having at its rear end a cam operating the raising mechanism proper of the copy holding member. The lever extends to a point adjacent the front edge of the typewriter frame, for manipulation by a sidewise push of the fingers in a way analogous to the carriage shift.

At a front corner of the base plate, near a corner of the typewriter frame, is a release key, connected through suitable linkage with means in the standard for returning the copy holding member to initial position when desired. The linkage includes a thin rod extending below the typewriter to near the base of the standard, and a bell crank at such point converting horizontal movement of the rod to a vertical movement such as to operate the release means.

The copy holder controls are virtually an extension of the keyboard itself, and maximum con-

venience is assured. These advantages are not obtained at the expense of any lessening in convenience elsewhere in the apparatus, as in folding it; in fact the invention affords a new and simplified provision for folding.

By virtue of the cam and bell crank construction, provision for dismounting of the standard (and the copy holding member thereon) is markedly simplified. The lower end of the standard is adapted to be locked in position by suitable supporting means, on the rear part of the base plate, in such manner that it can simply be lifted up and turned sidewise for taking down the copy holder.

15 In the accompanying drawings there is shown, more or less diagrammatically, one example of a specific embodiment of apparatus within the purview of the invention. In the drawings,

Fig. 1 is an isometric view of the copy holder, in position for use,

Fig. 2 is a view in side elevation corresponding to Fig. 1;

Fig. 3 is a view in front elevation, with some parts broken away for clarity, of the standard and copy holding member by themselves,

25 Figs. 4, 5 and 6 are fragmentary views to an enlarged scale of a portion of Fig. 3, showing the arrangement of parts for raising and lowering the copy holding member, and

30 Fig. 7 is a schematic view in front elevation of the rear portion of the copy holder, to show how the standard and copy holding member can be folded down.

Referring to the drawings, and especially to Fig. 1, the copy holder includes a base plate 10, of sheet metal, plastic or the like, upon which rest the rear feet of a typewriter 11 or other machine with which the copy holder is intended for use. The base plate can take a wide variety of sizes or shapes depending on particular requirements, and is held down firmly by the machine itself. The plate extends somewhat beyond the typewriter at front and rear, as shown in Fig. 2.

45 At the rear of the base plate is secured a pair of rails 12, grooved at 13, for reception of laterally spaced pairs of pins 14 and 15 (Figs. 2 and 3) projecting from a beam 16, upon which is mounted the copy holding assembly. This assembly includes a standard member 17, of panel shape with channeled edges 18 and a flanged bottom 19 secured to beam 16 as by screws 20. A copy holder member 21 with channeled edges 22 is provided, in telescopic sliding relation to the standard member, and having a spring clip 23 at its upper end to hold notebooks, paper or other copy, not shown. A stationary line indicating device 23 is attached to the standard member.

55 The means for raising the panel 21 includes a lift bar 24, guided in a bracket 25 near its upper end and in a clip 26 near its lower end; a spring 27 serving to hold the bar in the clip and also

to assist gravity in moving the bar down after each stroke. The upper end of the bar engages a pair of jacks 28 and 29, perforated to make an oversize but rather close fit with a lift rod 30 guided in a perforate flange 31 adjacent the top of standard 17 and secured to the top of the copy holding member, at 32.

At the front end of the base plate is secured a slotted guide 33, through which extends the front end of a lever 34, pivoted at 35 to the base plate, in the rear portion thereof, and carrying a cam 36, engaging a roller 37 on the lower end of the lift bar 24. To raise the copy holding member, the lever is moved to the left (Fig. 1). A spring 38 returns the lever to its normal position, and an adjustable bumper stop 39 determines the throw of the lever and thereby the vertical movement of the member 21 for each swing of the lever. The range of movement shown is sufficient to accommodate almost any copy spacing, including one, two and three line typewriter spacing and the spacing of stenographer's notebooks.

The relative lever arm lengths shown in Fig. 1, that is the ratio of the distance between pivot 35 to the front end of the lever, to the distance of the pivot to the cam, are quite convenient, but they can be changed if desired.

The horizontal lever movement as described is in practice exceptionally convenient for the operator. It is analogous to the operation involved in returning the typewriter carriage at the end of each line. If desired, cam 36 and spring 38 can be reversed right to left so that the lever movement is in the same direction as the carriage return movement.

In use, the disposition of the apparatus parts is initially as in Fig. 1. On reaching the end of each line of the copy, the operator swings the lever to the left, moving the copy holding member up by one line width. When it is desired to return the apparatus to original position, the operator presses a key 40, pivoted to the end of the guide 33, and connected through a rod 41 with a bell crank 42, mounted on a bracket 43 near the rear guides 12 and engaging the foot 44 of a release rod 45. The release rod is frictionally held and guided by means of a clip 46 and bracket 25 as shown. On pushing key 40, rod 45 moves up (Fig. 6) to release the jacks 28, 29 from the lift rod 30, whereby to let member 21 drop to the position shown in Fig. 1.

Jack 29 is pivoted loosely at 49 to the upper end of lifting bar 24, while jack 28 has a fork end 50 guided on the bar. With the lever 34 to the right, in the position shown in Fig. 1, the disposition of the jacks is as shown in Fig. 4. On moving lever 34 to the left, jack 29 engages and lifts rod 30, raising member 21 as is apparent from Fig. 5; the rod simply slides through the bore of jack 28. When lever 34 moves back to the right, jack 28 keeps the rod from moving down, while the right end of jack 29 drops freely, resuming the position shown in Fig. 5. The setting of bumper 39 determines the vertical increment of movement of copy holding member 21 on each shift of lever 34. When release rod 45 is operated, jacks 28 and 29 are raised sufficiently to let rod 30 slide through them (Fig. 6). To lower the copy holding member it is only necessary to press key 40 momentarily; it does not have to be held down.

Rod 30 operates in a pneumatic cylinder 51, spring mounted at 52, to cushion the fall of member 21. In the lowest position, the edge of member 21 strikes a felt bumper 53, on foot 44 to

return rod 45 to its initial position as seen in Fig. 2.

The standard is braced in vertical position by a bracket 54, carrying a thumbscrew 55 engaging a threaded block 56 on the rear of the standard (Fig. 2).

To fold down the standard and copy holder assemblage after use, screw 55 is unscrewed from the block, and the standard is moved to the right (Figs. 1 and 7) until pins 14 come opposite a corresponding pair of notches 57 (only the front notch being shown in the figures) whereby the right side of the standard can be lifted up and the standard at the same time rotated toward the left, until it reaches the position marked "folded position" in Fig. 7. Then screw 55 is tightened up to hold the apparatus in closed position; the screw engaging a small depression 58 (Fig. 2) in the back of member 17. Stop 59 limits movement of the standard and copy holding member assembly, to the right. In setting up the assembly, the described operations are reversed. The groove 13 in rear guide 12 terminates short of the left end, leaving a solid portion 60 (Fig. 1) which serves as a stop limiting the movement of the assembly toward the left, when the apparatus is set up.

To disengage this assembly entirely from the base, it is merely necessary to move the assembly to the intermediate position shown in Fig. 7 and then keep sliding it to the right until pins 15 come opposite notches 57, whereupon the assembly can be lifted away from the base.

A dog 61, near the upper part of standard 17, engages a perforation 62 in one of channels 22 when the copy holding member 21 reaches the top of its range of movement, to prevent accidental disengagement. To remove the copy holding member nut 32 is removed and dog 61 is pressed with a match or the like, whereupon the copy holding member can be lifted clear of the standard.

What I claim is:

1. In a copy holder, a base adapted for association with a machine and including a portion which extends below the lower surface of the machine to a point adjacent the front of the machine, an upwardly extending standard member in fixed relation to the rear portion of the base, a member in vertically movable relation with respect to the standard member, one of said members being provided with copy holding means and the other with line indicating means, means operable from a point adjacent the lower end of the standard member, for moving the movable member with respect to the standard member, an operating member reciprocable laterally in a horizontal plane along the front of the machine to operate said moving means and extending adjacent the base below the level of the machine to a point adjacent the front of the base, and means secured to said frontwardly extending portion of the base, for adjustably limiting the extent of reciprocatory movement of the reciprocable operating member.

2. In a copy holder, a base adapted to underlie a machine, an upwardly extending standard member in fixed relation to the rear portion of the base, a member in vertically movable relation with respect to the standard member, one of said members being provided with copy holding means and the other with line indicating means, means operable from a point adjacent the lower end of the standard member, for lifting the movable member with respect to the standard member,

means operable from a point adjacent the lower end of the standard member for releasing the movable member and causing it to drop, operating means laterally reciprocable in a horizontal plane, in operative relation to said lifting means and having a part for manual manipulation along the front of the machine, said operating means extending below the level of the machine to a point adjacent and below the front end thereof, and an operating means in operative relation to said releasing means, extending below the level of the machine to a point adjacent the front thereof.

3. In a copy holder, a base elongated in a front to rear direction, an upwardly extending standard member in fixed relation to the rear portion of the base, a copy holding member carried on the standard member for vertical movement with respect thereto, a lift member carried by the standard member in vertically reciprocable relation with respect thereto, lifting and holding means engaging the copy holding member and the lift member having an operating portion located adjacent said base, and constructed and arranged for lifting the copy holding member on upward movement of the lift member and for retaining the copy holding member against falling at the end of such movement, reciprocable operating means engaging said operating portion of the lift member, substantially centrally located on the base and extending adjacent said base from rear to front, constructed and arranged upon each operating movement of said operating means to lift the lift member, reciprocable means in the standard member, adapted in one position of reciprocation to release said lifting and holding means to cause the copy holding member to drop to bottom position, and manually operable means operably engaging said reciprocable release means, and extending along the base from rear to front.

4. In a copy holder, a base, an upwardly extending standard member in fixed relation to the rear portion of the base, a member in vertically movable relation to the standard member, one of said members being provided with copy holding means and the other with line indicating means, moving means operable from a point adjacent the lower end of the standard member, for moving the movable member with respect to the standard member by successive increments, a manually operable lever adjacent the base in pivotal relation thereto for movement in a horizontal plane, at a point such that the arm of the lever to the rear of the pivot is shorter than the arm to the front of the pivot and extending to a point adjacent the front of the base, and operating means on the rear part of the lever engaging said moving means, so constructed and arranged that movement of the lever through a relatively large distance operates said moving means a relatively small distance.

5. In a copy holder, a base, an upwardly extending standard member in fixed relation to the rear portion of the base, a member in vertically movable relation to the standard member, one of said members being provided with copy holding means and the other with line indicating means, means operable from a point adjacent the lower end of the standard member, for moving the movable member with respect to the standard member, a manually operable lever adjacent the base in pivotal relation thereto for movement in a horizontal plane and extending to a point adjacent the front of the base, and a cam on the rear portion of the lever engaging said moving means, the

cam surface being such that movement of the lever in one direction causes lifting of the moving means.

6. In a copy holder, a base, an upwardly extending standard member in fixed relation to the rear portion of the base, a movable member in vertically movable relation to the standard member, one of said members being provided with copy holding means and the other with line indicating means, moving means operable from a point adjacent the lower end of the standard member, for moving the movable member with respect to the standard member, a manually operable lever adjacent the base in pivotal relation thereto for movement in a horizontal plane, at a point such that the arm of the lever to the rear of the pivot is shorter than the arm to the front of the pivot and extending to a point adjacent the front of the base, operating means on the rear part of the lever engaging said moving means, so constructed that movement of the rear arm of the lever in one direction through a relatively large distance lifts the moving means a smaller distance, means for holding the movable member against downward movement, and release means for said holding means, operable from a point near the front of the base adjacent the front end of said lever.

7. In a copy holder, a base, guide means at the rear thereof extending transversely thereof, a standard member guided in said guide means and movable and rotatable with respect to the base between two positions one of which is normal vertical use position and the other of which is horizontal position, a movable member carried by and in vertically movable relation to the standard member, one of said members being provided with copy holding means and the other with line indicating means, moving means for the movable member, located in the standard member and extending down to near the level of the base and adapted on operation to move the movable member with respect to the standard member, horizontally reciprocable manually controlled operating means extending from operative contact with the moving means, to the front of the base, and so constituted that on moving the standard member to vertical use position the moving means is brought directly into operative relation to said horizontally reciprocable manually controlled operating means.

8. In a copy holder of the type described having an upwardly extending fixed standard member, a movable copy holding member in vertically movable guided relation with respect thereto, a lift rod secured to the copy holding member, a lift bar in vertically reciprocable relation to the standard member, and jack means in cooperative relation between the lift bar and the lift rod and so constructed and arranged that on upward movement of the lift bar the lift rod is moved up and on downward movement of the lift bar the lift rod is retained in its elevated position by the jack means; the improvement comprising means normally out of operative engagement with the jack means but adapted on manual operation to engage the jack means and cause the jack means to release the lift rod, means for retaining said engaging means in engaging position while the lift rod drops, and means in fixed relation to the copy holding member, operative to return said engaging means to inoperative position upon dropping of the lift rod and copy holding member to bottom position.
